C. J. Wiebusch INVENTOR

BY *Victor J. Evans*

ATTORNEY

UNITED STATES PATENT OFFICE.

CLARENCE JOHN WIEBUSCH, OF LAKE CITY, MINNESOTA.

CREAM COOLER.

Application filed March 26, 1927, Serial No. 178,739. Renewed February 14, 1929.

This invention relates to a cooling device for cream and other fluids, the general object of the invention being to provide a U-shaped member adapted to be placed in a receptacle containing a cooling medium, with means for introducing the fluid to be cooled in one end of the member, the other end of the member being shaped to form a siphon and this end delivers the cooled fluid into a receiver.

A further object of the invention is to make the down part of the member of a plurality of tubes, while the upper part is of but a single tube so that the fluid passes slowly through the member and is thus held in the cooling medium for a long time and by having a plurality of tubes, the radiating area is increased.

A still further object of the invention is to make the member of pipes and flexible tubing so that it can be easily manipulated and will hang straight when hung up so that it will drain easily and freely.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation showing the device in use, with the cooling tank and the receiving receptacle in section.

Figure 2 is a plan view of Figure 1.

Figure 3 is a view showing the device hung up to drain.

Figure 4 is a view taken a quarter turn from Figure 3.

Figure 5 is a longitudinal sectional view through the funnel supporting receptacle.

Figure 6 is a sectional view through the funnel.

In these views, 1 indicates a receptacle which has its lower end extended at one side thereof, as shown at 2, on which is placed

a hook 3 for holding the receptacle at the top of a tank A which contains the cooling medium. The receptacle 1 is provided with an internal collar 4 which has its inner circumference beveled and ground to engage a similar annular surface 5 formed on a funnel 6 so that the funnel is supported in the receptacle, with a liquid-tight joint between the parts. A flexible tube 7 is connected with the spout of the funnel and the other end of the tube engages the inlet nipple 8 of a coupling 9 which is formed with the four outlet nipples 10. Four pipes 11 are connected together in spaced relation by the clamps 12 and the upper ends of these pipes are connected with the discharge nipples 10 by the tubes 13. A coupling 14, similar to the coupling 9, is connected with the lower ends of the pipes 11 by the tubes 15 and the discharge nipple of this coupling 14 is connected by a tube 16 with a pipe 17 which is connected by a tube 18 with a pipe 19, the outer end of which is weighted, as at 20. A drip receiver 21 is carried by the pipe 17 and a hook 22 is also carried by said pipe 70 adjacent its upper end.

The device is inserted in the tank A which contains the cooling medium, as shown in Figure 1, so that the parts assume the shape of a U, with the tube 18 and the pipe 19 forming a siphon, the pipe 19 extending into the receiving receptacle B which is placed alongside the tank A. The hook 22 is placed over the edge of the tank A, as shown in Figure 1. Thus when the cream or other fluid is placed in the receptacle 1, it will flow through the funnel and into the coupling 9 where it will be divided into four streams, each stream passing down a pipe 11. The streams come together again at the coupling 14 and pass upwardly through the return pipe 17 and through the tube 18 and pipe 19 into the receiving receptacle B. The fluid, passing through the down part of the device, composed of the pipes 11, will divide into small streams so that the cooling medium can readily absorb the heat from the liquid and the flow of the liquid is checked as it must pass from the four pipes into the single return pipe. Thus 100

the liquid is held in that part of the device which is immersed in the cooling medium for a considerable time so that it will be thoroughly cooled before being discharged into the receiver B.

After the device has been used, it may be hung up, as shown in Figures 3 and 4, so that the parts will hang straight and thus they can be easily cleaned by pouring cleaning fluid through them and the parts will drain readily, as will be seen. Any liquid remaining on the exterior parts will be caught by the receptacle 21 and thus be prevented from running on to the floor of the room where the device is hung up.

This device can receive the cream directly from the separator so that it will cool the cream immediately and thus check the growth of bacteria. The device is easy to 20 keep clean and can be manufactured to sell at low cost.

It is thought from the foregoing description that the advantages and novel features of my invention will be readily apparent.

25 I desire it to be understood that I may make changes in the construction and in the combination and arrangement of the several parts, provided that such changes fall within the scope of the appended claims.

30 What I claim is:—

1. A cooling device comprising a receiving receptacle having a funnel-shaped bottom, a coupling, a flexible tube connecting the coupling with the funnel-shaped bottom, 35 said coupling having a plurality of discharge nipples, a plurality of pipes, flexible tubes connecting each pipe with a discharge nipple, a coupling having a plurality of inlet nipples, flexible tubes connecting the inlet nipples with the lower ends of the pipes, a return pipe, a flexible tube connecting the same with the second coupling, a discharge pipe and a flexible tube connecting the same with the return pipe.

40 2. A cooling device comprising a receiving receptacle having a funnel-shaped bottom, a coupling, a flexible tube connecting the coupling with the funnel-shaped bottom, said coupling having a plurality of discharge nipples, a plurality of pipes, flexible tubes connecting each pipe with a discharge nipple, a coupling having a plurality of inlet nipples, flexible tubes connecting the inlet nipples with the lower ends of the pipes, a return pipe, a flexible tube connecting the same with the second coupling, a discharge pipe, a flexible tube connecting the same with the return pipe, hooks on the return pipe and on the receptacle adapted to 45 engage the top of a cooling tank in which the device is adapted to be placed and a drip receiving receptacle on the return pipe.

60 In testimony whereof I affix my signature.

65 CLARENCE JOHN WIEBUSCH.
